CLAIM

We claim the ornamental design for a safety lock for a knife storage block, as shown and described.

DESCRIPTION

FIG. 1 is a right side view in elevation of a safety lock for a knife storage block showing our new design, the left side view being a mirror image thereof;

FIG. 2 is a front perspective view thereof showing the design in its locked position; and,

FIG. 3 is a front view in elevation thereof showing the design in its unlocked position.

The broken line showings in FIGS. 1 and 2 are environmental only and form no part of the claimed design.
